DESIGN FOR A CHAIR OR SIMILAR ARTICLE

Harry J. Terker, Brooklyn, N. Y.

Application June 27, 1936, Serial No. 63,542

Term of patent 7 years

To all whom it may concern:

Be it known that I, Harry J. Terker, a citizen of the United States and residing at Brooklyn, in the county of Kings and State of New York, have invented a new, original, and ornamental Design for a Chair or Similar Article, of which the following is a specification, reference being had to the accompanying drawing, forming part thereof, and in which

The figure shows a perspective view of a chair having two side frame members taking the form of U's on their side, the lowermost legs of the U resting upon the floor and the uppermost legs of the U forming side arms for the chair. The detachable seat and back is supported at the vertical base of the U and at the rear of the upper legs of the U.

The lower legs of the U are connected at their rear ends.

What is claimed is:

The ornamental design for a chair or similar article substantially as shown and described.

HARRY J. TERKER.
